(57) **CLAIM**

We claim the ornamental design for a bottle, as shown and described.

DESCRIPTION

FIG. 1 is a perspective view of a bottle showing our new design;

FIG. 2 is a right or left side elevation view thereof;

FIG. 3 is a front or rear elevation view thereof;

FIG. 4 is a top plan view thereof; and,

FIG. 5 is a bottom plan view thereof.

The broken lines defining the bounds of the claim form no part thereof.

1 Claim, 4 Drawing Sheets
